Primary Examiner — Jeffrey D Asch(74) *Attorney, Agent, or Firm* — NSIP Law**CLAIM**

The ornamental design for a mobile phone, as shown and described.

DESCRIPTION

FIG. 1 is a front perspective view of a mobile phone showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a rear perspective view thereof.

The broken lines shown in the figures that are immediately adjacent to the shaded areas and define unshaded regions, represent the bounds of the claim, while all other broken lines, including the four tiny circles at the top front near the speaker opening are directed to environment; the broken lines form no part of the claimed design.

The shade lines in the figures show contour and not surface ornamentation.
